UNITED STATES PATENT OFFICE.

WILLIAM A. SCHRAUBSTADTER, OF ST. LOUIS, MISSOURI.

TYPE-PERFECTING MECHANISM.

No. 821,127.

Specification of Letters Patent.

Patented May 22, 1906.

Application filed April 20, 1903. Serial No. 153,436.

To all whom it may concern:

Be it known that I, WILLIAM A. SCHRAUBSTADTER, a citizen of the United States, and a resident of the city of St. Louis and State of Missouri, have invented certain new and useful Improvements in Type-Perfecting Mechanism, of which the following is a specification.

My invention relates to type-perfecting, and has for its principal objects to perform the perfecting operations at a distance from the type-casting mold, to perfect the type singly, to accomplish certain results heretofore accomplished only by hand-labor, to provide for securing type with the "jet" thereon, and to attain certain other advantages hereinafter disclosed.

In the accompanying drawings, which form part of this specification, and wherein like symbols refer to like parts wherever they occur, Figure I is a vertical view of my perfecting mechanism applied to a type-casting machine, which is shown in section. Fig. II is an end elevation thereof, and Fig. III is a side elevation of said perfecting mechanism. Fig. IV is a plan view of the perfecting mechanism, the device for connecting it to the actuating mechanism being broken away. Fig. V is a vertical sectional detail through the type-ejecting plunger of the forming mechanism and the pusher-bar of the type-gripping carrier of the perfecting mechanism.

Heretofore type-casting machines have been devised which comprised, among other parts, actuating mechanism and a reciprocating mold-cover, the mold-cover being provided with a jaw in which the type remains while undergoing some of the operations of the machine thereon. On account of the necessarily short stroke of the mold-cover some of the perfecting devices in such machines were located on or so close to the mold that there was great danger of chips flying into the mold.

In the present invention the casting mechanism A is preferably of the construction fully described in my copending application for Letters Patent therefor, No. 154,130, filed April 24, 1903. The perfecting mechanism, while coöperating with the casting mechanism A, is removed therefrom, but is arranged to be actuated by the same actuating mechanism and is adapted to receive the type directly from the jaw 1 of the mold-cover 2.

For this purpose an arm 3 is mounted to oscillate in a vertical plane and in such a posi-

tion that when said arm is upright its upper end is directly below and in register with the jaw 1 of the mold-cover 2 of the type-casting mechanism. Mounted in a longitudinal 60 socket in said oscillating arm so as to slide endwise thereof is a pusher-bar 6. This pusher-bar has a pin 7 projecting through a slot in said arm and is provided with a spring 8, which is under compression and bears at 65 one end against said pin and at its other end against a lug 9, provided therefor on the outer end of said arm, whereby said spring tends to force said pusher-bar back toward the pivotal end of said oscillating arm. The 70 outer end of the pusher-bar has lateral extensions, and the end of the oscillating arm is grooved to permit the extending end of the pusher-bar to enter therein. This groove is arranged to be in direct register with the 75 clamping-jaw of the mold-cover when the oscillating arm is in its vertical position. In order to determine the proper vertical position of said arm, a screw 10 is located on the frame of the casting-machine in position for 80 the oscillating arm to bear against. Said screw thus constitutes an adjustable stop for limiting the vertical position of said arm.

The arm 3 is mounted upon a shaft 10^a, which is provided with a crank-arm 11, which 85 in turn is connected by a pivotal link 12 to a lever 13, having a fulcrum 13^a in the main frame and arranged to be actuated by a cam 14 on a shaft 15 of the actuating mechanism. The connecting devices are so arranged as to 90 produce a rocking or oscillating motion of the arm 3 through an arc of about ninety degrees, more or less. Also suitably connected to the actuating mechanism so as to be driven thereby is a rock-lever 16, whose end is in position to bear against the projecting pin 7 of the pusher-bar 6 when the oscillating arm 3 is in its lowermost or horizontal position. For this purpose the rock-lever 16 is fulcrumed 95 on a shaft 16^a, mounted on the frame of the 100 perfecting mechanism so as to swing in a vertical plane, and its end is connected by a pivotal link 17 to a lever 17^a, having a fulcrum 17^b in the main frame in position to be operated by a cam 18 on a shaft 15 of the actuating mechanism. The power-transmitting devices are so arranged that the rock-lever 16 will actuate the pusher-bar 6 on the arm 3 as soon as said pusher-bar reaches its horizontal position.

The outer end of the oscillating arm 3 is beveled on its under side. Fixed to the frame-

work in position to limit the downward movement of said oscillating arm is a back-stop 19, beveled to correspond with the beveled outer end of said oscillating arm. This back-stop 5 19 constitutes one wall of a vertical channel. The opposite wall 19^a of said channel is adjustably mounted upon said frame so as to be movable to accommodate type of various widths. For this purpose the wall of the 10 channel has an elongated slot 20 therein, through which headed clamping-screws 21 extend into the framework. The rear portion of the piece which constitutes the channel-wall has a flange overlapping the framework. 15 In order to decrease the width of the channel, a threaded bolt 22 extends through said flange into the framework and serves to draw said flange toward said framework. In order to widen said channel, said flange has a 20 threaded hole through which works an adjusting-screw 23, arranged to bear against the framework and force said flange away therefrom. By this means the vertical channel may be adjusted to any desired width.

25 The vertical channel has perfecting-knives 24, arranged on each side thereof, said knives comprising sharp-edged plates slotted lengthwise and set at an angle to the walls of the channel. Said plates 24 are clamped by 30 means of screws 25, so that all that is necessary for adjusting them is to loosen the screws and shift said plates endwise and again clamp them in any desired position.

35 Mounted above the vertical channel so as to slide therein is a T-bar or plunger 26, whose end portion fits in said channel and constitutes a plunger for forcing a type therein to the lower end of said channel. This last- 40 mentioned plunger 26 is actuated by the driving mechanism, from which motion is transmitted to it by any suitable transmitting devices. As shown in the drawings, said plunger 26 has a pin 27 projecting through a slot 28 in the portion 45 of the framework, 45 which constitutes a guide therefor and is connected by a pivotal link 29 to a lever 30, having a fulcrum 30^a on the main frame in position to coöperate with a cam 31, provided therefor on a shaft 15 of the driving mechanism. The parts are so arranged that the 50 downward movement of the plunger 26 occurs just after the type has been forced into the top of the channel by the operation of the pusher-bar 6. At the lowermost portion of said vertical channel is a horizontal channel 55 32, adapted to receive the type directly from said vertical channel. The walls of this horizontal channel are provided with perfecting-knives 33, similar to those provided for the 60 vertical channel, and the walls of said horizontal portion and the perfecting-knives thereon may be made adjustable, as in the case of the walls and knives of the vertical channel. Opposite the lower end of said vertical channel is a horizontal pusher 34, mount-

ed in guides provided therefor in the framework to slide in alinement with the horizontal portion of said channel. This pusher 34 has pins 35 projecting laterally therethrough, which rest between the forks of a yoke 36. 70 The stem 37 of this yoke works in a socket provided therefor in the end of one arm of a bell-crank lever 38. In this socket is a spring 39, arranged to press said yoke outwardly to keep it in engagement with said pins. The 75 other end of said bell-crank lever is connected by a pivotal link 40 to a lever 41, fulcrumed on the main frame and arranged to bear against a cam 42 on a shaft 15 of the actuating mechanism. The parts are so arranged that the horizontal pusher-bar 34 is moved forward just after the vertically-moving pusher-bar has reached the lower limit of its stroke, so that the type at the bottom of the vertical portion of the channel is forced into 80 the horizontal portion thereof and the entire row of type in said horizontal portion is moved bodily to pass the perfecting-knives 33. The several parts which coöperate with the several cams are preferably held in engagement therewith by means of springs 43, 85 suitably arranged for the purpose.

The machine is provided with a knife or sharp-edged bar 44, arranged to project into position for a type in the jaw of the mold-cover 90 to be carried against it by the movement of said mold-cover. This knife 44 thus removes the jet formed on the end of the type by the operation of casting. Heretofore the jet-breaker has been mounted fixedly with reference to the mold of the casting-machine; but as it is desirable occasionally to obtain type with the jet thereon the jet-breaker is preferably mounted on a part which is movable or separable from the casting mechanism. As 100 shown in the drawings, the jet-breaker is mounted upon the frame 47 of the perfecting mechanism.

The frame 47 of the perfecting mechanism is mounted to slide in guides provided therefor in the bracket 48 or other portion of the main frame of the machine provided for its support. The guides, as illustrated in Figs. I and II of the drawings, may consist of a horizontal rib 49 in the side of the supporting-bracket 48, the rib being arranged to fit a groove provided for the purpose on the frame 47 of the perfecting mechanism. The perfecting mechanism is slidingly held in position upon the supporting-bracket by means 110 of a hook 50, which is secured thereto and overhangs the top of said supporting-bracket. An elongated horizontal slot 51 is formed in the frame of the perfecting mechanism, and through this slot extends a threaded bolt 52, 115 which secures the perfecting mechanism firmly to the supporting-bracket. The devices for transmitting power from the actuating mechanism to the perfecting mechanism have separable connections. For in- 120 125 130

stance, the pin or screw-bolt 46, which secures the lever 16 to the link 17, is made removable or detachable. So, too, the pins or screw-bolts 46, which secure the respective links 12, 29, and 40 to their respective actuating-levers 13, 30, and 41, are made removable.

Obviously the mechanism hereinbefore described admits of considerable modification without departing from my invention, and I do not wish to be restricted to the specific mechanism shown or described.

What I claim is—

1. A type-making machine comprising a mold, a reciprocating mold-cover adapted to receive the type directly from the mold, a type-carrier, a type-channel, and perfecting-knives arranged along the path of said type, said type-carrier being arranged to receive the type from said mold-cover and to deliver them singly into said passage-way.

2. A type-making machine comprising a mold, a reciprocating mold-cover adapted to receive the type directly from the mold, a type-carrier, a type-channel, and relatively adjustable perfecting-knives arranged along the path of said type, said type-carrier being arranged to receive the type from said mold-cover and to deliver them singly into said passage-way.

3. In a machine for making type, the combination of type-casting mechanism and type-perfected mechanism, said type-perfected mechanism comprising a type-channel having its admission portion and its delivery portion transverse to each other, perfecting-knives alongside the said portions, means for delivering type into and through said channel, said means comprising an oscillating carrier-arm adapted to receive the type from the casting mechanism and carry it to a point opposite the admission end of said channel, and pusher-bars arranged to be actuated by the actuating mechanism to push said type into and through said channel.

4. In a machine for making type, the combination of type-casting mechanism and type-perfected mechanism, said type-perfected mechanism comprising a type-channel having a vertical portion and a horizontal portion, perfecting-knives alongside the said portions, and means for delivering type into and through said channel, said means comprising an arm mounted to swing in a vertical plane below the delivery end of the casting mechanism and adapted to receive the type therefrom in its upright position and also adapted to carry said type to a point opposite the delivery end of said channel and pusher-bars arranged to be actuated by the actuating mechanism to push said type into and through said channel.

5. In a machine for making type, the com-

bination of type-casting mechanism and type-perfected mechanism, said type-perfected mechanism comprising a type-channel having a vertical portion and a horizontal portion, perfecting-knives alongside of said portions, and means for delivering type into and through said channel, said means comprising a vertically-oscillating type-carrier arm having a groove and socket in its end and a pusher-bar therein, and means for operating said pusher-bar when said arm is in its horizontal position to force the type from its groove into said channel.

6. In a type-making machine, the combination of type-casting mechanism and type-perfected mechanism movable relatively thereto, and a jet-cutter arranged on the type-perfected mechanism so as to be movable with said type-perfected mechanism and in position to remove the jet from the type before said type is delivered to the perfecting mechanism.

7. In a type-making machine, the combination of a type-casting mechanism, and a type-perfected mechanism, and a jet-cutter mounted on the type-perfected mechanism in position to remove the jet from the type before it is delivered to the perfecting mechanism.

8. In a type-casting machine, the combination of a member provided with a mold-cavity, an oscillating carrier provided with a type-receiving channel, a raceway, means for delivering type to said carrier, an ejector operating in said channel, and means for operating said ejector, substantially as described.

9. In a type-casting machine, the combination of a member containing a mold-cavity, a raceway, an oscillating carrier, means for delivering type to said carrier, and an ejector on the carrier adapted to permit the same to receive the type and operating to deliver said type to the raceway, substantially as described.

10. In a machine for making type, the combination of type-casting and type-perfected mechanism, said type-perfected mechanism comprising a raceway having a vertical portion and a horizontal portion, perfecting-knives along said raceway, and means for delivering type into and through said raceway, said means comprising a vertically-oscillating type-carrier having a type-receiving channel and an ejector therein and means for operating said ejector, when the type-receiving channel is in a horizontal position, to force type from said carrier into said raceway, substantially as described.

St. Louis, Missouri, April 18, 1903
